SKIN DIVING INSIGNIA

Erwin Feuer, Miami, Fla. (½ Interwagen Corporation,
8819 SW. 129th Terrace, Kendall, Fla. 33156)

Filed Apr. 13, 1973, Ser. No. 350,725

Term of patent 14 years

Int. Cl. D11—02

U.S. Cl. D29—2 R

FIG. 1

FIG. 2

FIG. 1 is a front elevational view of a skin diving insignia showing my new design, color being depicted schematically for ease of illustration;

FIG. 2 is a side elevation of the insignia shown in FIG. 1; and

FIG. 3 is a rear view of the insignia.

I claim:

The ornamental design for a skin diving insignia, substantially as shown and described.
